FIG. 7.

FIG. 5

Thomas C. Spelling INVENTOR.

UNITED STATES PATENT OFFICE.

THOMAS C. SPELLING, OF NEW YORK, N. Y.

FOUNTAIN-PEN.

1,379,057.

Specification of Letters Patent. Patented May 24, 1921.

Application filed November 6, 1918. Serial No. 261,420.

To all whom it may concern:

Be it known that I, THOMAS C. SPELLING, a citizen of the United States, residing at New York city, in the county of New York 5 and State of New York, have invented certain new and useful Improvements in Fountain-Pens, of which the following is a specification.

This invention relates to mechanisms for recording letters and figures on paper, parchment, or the like, and belongs to the class bearing the designation of fountain pens. Its purpose is the provision of a fountain pen of simpler and cheaper construction and yet superior in points both of convenience and effectiveness to any now in use. It only is required to describe the parts and functions of the present device, to expose the defects and inconveniences of those now in use. This invention embodies a writing implement which utilizes all the progress and improvements in pen-points and writing fluid which had been made before the fountain pen now used was invented, but which cannot be used with fountain pens, because the fountain pen-point must have a peculiar formation different from the common penpoint; and for its use, ink of particular ingredients and consistency is required. But for this device any one of a score or more kinds of points, and particularly, any of the many brands of ink manufactured for common use can be used. Not only are valvular filling, clogging, smearing and inferior penmanship here obviated, but superiority of convenience, safekeeping, durability and cleanliness are obvious characteristics, all of which will be explained in this specification, and pointed out in the claims, in connection with the drawings.

Figure 1 is a top view of the device. Fig. 2 is a partly sectional side view of the device put together for carrying it in a garment pocket, or other receptacle. Fig. 3 is a side elevation of the device ready for use except that the two sections of the pen holder are slightly separated, penpoints being shown. Fig. 4 is a view of either side of the upper section of the holder and of the ink receptacle, showing a modification in the means by which said two parts are secured together. Fig. 5 is the upper portion of the tube shown in Fig. 4, looking at either the right or left of it. Fig. 6 is a top view of the lower section when held upright as in the lower part of Fig. 3, with

pen points in the central opening therein. Fig. 7 illustrates still another modification of the fastening means.

Numerals will be used herein to designate parts, as an aid to description, the same numeral designating identical parts in the different views.

The cap 31, should be formed of metal, or any durable substance. The mouth 1, 65 has a short cylindrical section, 2, and a section, 3 above that, the sides of which are outwardly and upwardly slanted, giving it the shape of a diminutive ink well; in other words the cap, when not used as such, 70 serves as an ink well. Four arms, 5, are attached to the top surface, 4, of this member, with pins, the heads of which are designated by reference numerals, 6. The dotted lines, 32 in Fig. 1 show these arms 75 turned out to increase base area, in detached use. In the same figure the arms are seen in locked relation. In order to free them from the locked relation, to be turned out, it is necessary that one of them be formed 80 of resilient substance, because, in turning an arm out, the free end of the one arm must be sprung upward and the arm slid over one of its fellows. When one arm has been turned out, there is nothing to interfere with 85 revolving the others on the pins, serving as pivots, and likewise turning them out.

In two opposite sides of the cylindrical section, 2, of the cap are formed the slots, 7. To secure perfect engagements of the 90 hook, 26, as well as to facilitate its disengagement, the edges above and below the slot are conversely slanted, the lower edges outward and upward, and the upper edges downward and inward.

In view of the possibility that some users may prefer to keep it in a receptacle, the incisions, 25, are made in the sides of the cap, near the top, and into these, the tips of a finger may be inserted to raise it out of 100 any compartment.

The stopper, 27, may be formed of any suitable material, but preferably of rubber, cork or the like. It will have formed on it the shoulder, 8, around the middle.

The closure-means presently more fully described requires that the cap be fitted on the top of the penstock with yielding but strongly resisting pressure, in order that the cap fastener can be given firm binding effect. And that result is attained by the combination of the compression of this

shoulder due to the resilient force of the binding arms, 16.

The stopper, 27, has ends identical in shape and size, the stopper being cylindrical. Either end is adapted to be fitted into the top, 11, of the penholder or into the mouth 1, of the cap. But the end fitted into the top of the penholder should be firmly fastened and held therein, either with a transverse locking pin or otherwise. The upper member, 12, of the penholder, tubular in form, is preferably made of thin sheet metal, though celluloid, hard rubber, or the like could be used. The edges, 13, of the tube indicate that from the point, 14, to the base, the substance of the tube is left disunited, the purpose of which is to impart flexibility, needed for the gripping and holding of the lower member 15, of the penstock. The binding arms, 16, are formed in the upper member to grip and hold the cap in place. Since these are identical in form and coact in use, a description of one will suffice. It will be soldered or otherwise attached to the substance of the upper member, as seen at 17. It is curved upward at 18, and forms the elbow, 24, and beyond that, it resumes a vertical direction, and on that part is formed the short hook, 26, of suitable dimension to fit into, and engage, slot 7. The arm, 16, in normally bent position, should fall short of reaching into the slot, 7, so that the shoulder, 8, must be pinched between the end of the penholder and end of the cap in order to snap the hook, 26, into place, causing resilient frictional engagement. This formation of the arm is such that pressure on the curve, 18, moves the hook, 26, on the surface of the perpendicular section, 2, of the cap until it snaps into the slot, 7. To release the engagement, further and additional pressure is applied to the curve, which moves the hook upward and out of the slot, that being the result of the approach of the curve to a vertical relation and of the contact of the elbow with said surface. In this act, the penholder may be partially revolved on the stopper, to cause the hook to rest on unbroken surface of the cap and thus prevent reengagement in the act of separation.

The lower member, 15, of the penholder carries the shield, 21, suitably attached at its upper terminal. The shield may be formed and adapted in the usual way for carrying a penpoint. But if the lower member be of suitable material, it and the shield may be of a single piece. This lower member is formed with the narrow enlargement, 22, extending around it. In the end other than that carrying the shield, is the opening, 23, wide enough and of sufficient length to admit of the placing therein and retention of several penpoints (which may be of the same make or of different kinds,) or of penpoints and a penwiper, or other small article. The enlargement, 22, limits and arrests the movement of the lower member when it is slid into the upper member, both before and after use.

The terminal cap, 9, protects the terminal, 20, of the lower member. When the device is to be used it should be removed and fitted on the stopper where it serves to protect the user's hand from ink stain. This cap also confines the penpoints, etc. within the penpoint chamber, 23. It is slotted as shown at 33 to impart to it gripping force.

When the device is to be used, it is stood on the cap, the base arms, 5, first being turned out. Pressure of the fingers of one hand on the upward curves, 18, of the binding arms, causes the hook, 26, to rise out of the slot, 7. With the fingers of the other hand, the penstock is now separated from the top cap, containing ink, the lower member is extracted and reversed, the terminal cap removed and transferred to the stopper, the shorter end 20 of member 15, below the enlargement, is inserted in the upper member. A penpoint, 10, taken from the open end and inserted in the shield completes the preparation for writing.

When use of the device is suspended the replacement of the parts is accomplished by a reversal of the process of preparation.

The quantity of ink to be carried within the cap will of course depend upon its interior dimensions, which is subject to the option of the manufacturer. But a very slight increase of horizontal diameter in the expanded portion beyond the diameter of the mouth will afford capacity for sufficient ink for a great amount of writing.

The modification illustrated in Fig. 4 consists merely in the provision of plain hooks, 28, attached to the cap at 29, and formed and dimensioned to engage slanted shoulders, 30, formed on or attached to the cap.

The fastening means illustrated in Fig. 7 comprises the opening 34, in the side of the cap at the base, the binding arm, 35, to automatically and frictionally engage it upon turning the cap toward it, and the ring, 36, resting on the penholder. Two such fasteners, oppositely disposed, may be provided. The ring, 36, is held by cross pin, 37, and frictional engagement occurs at 38.

Inasmuch as the invention may be embodied in various other forms of varying sizes, I do not, by reason of the foregoing description and these drawings, preclude myself of the right to embody it in other forms, and to supply it to other uses, consistently with these specifications and claims.

Having now fully described my invention, I claim as follows:

1. A writing implement comprising a

tube, a cap, a member carrying a shield for a penpoint, and a stopper, the tube and cap detachably secured to each other on the stopper.

5 2. A writing implement comprising a tube, a cap, a member carrying a shield for a penpoint, and a stopper, the shield carrying member formed with interior space in the end opposite that carrying the shield, for 10 storage of penpoints and other small articles.

3. In a writing implement comprising a tube, a cap, a shield carrying member, and a stopper, means for binding and impacting the tube and cap oppositely on an encircling 15 exterior shoulder of the stopper.

4. In a writing implement comprising a tube, a cap, a shield carrying member, and a stopper, means for binding and impacting the tube and cap oppositely on an encircling 20 exterior shoulder of the stopper, the means consisting of oppositely positioned resilient arms securely attached to the tube, the arms having detachable engagements in notches in the neck of the cap.

25 5. In a writing implement comprising a tube, a cap, a shield carrying member, and a stopper, means for binding and impacting the tube and cap oppositely on an encircling exterior shoulder of the stopper, the means 30 consisting of oppositely positioned resilient arms securely attached to the tube, the arms having detachable engagements in notches in the neck of the cap, each arm formed with an upward curve, a downwardly projected 35 elbow, a straight section, and an in-turned hook.

6. In a writing implement comprising a tube, a cap, a shield carrying member, and a stopper, means for binding and impacting 40 the tube and cap oppositely on an encircling

exterior shoulder of the stopper, the means consisting of oppositely positioned resilient arms securely attached to the tube, the arms having detachable engagement in notches in the neck of the cap, each arm formed with 45 an upward curve, a downwardly projected elbow, a straight section, and an inturned hook each hook suitably formed and positioned in place for engagement with a notch in the neck of the cap. 50

7. A writing implement comprising a tube, a cap, a shield carrying member and a stopper, and means for increasing the top area of the cap, in detached use.

8. In a writing implement comprising a tube, a cap, a shield carrying member and a stopper, means for increasing the top area of the cap, in detached use, and means consisting of flat arms pivoted in and on the top of the cap and converged to interlocked 60 relation, centrally, the pivot for each arm positioned near the exterior edge of the top of the cap, the section of each arm exterior to the pivot being shorter than the section interior to the pivot when in interlocked 65 relation.

9. In a writing implement comprising a tube, a cap, a shield carrying member and a stopper, means for increasing the top area of the cap, in detached use, the means consisting of flat arms pivoted in and on the top of the cap and converged to interlocked 70 relation, centrally, one of the interlocking arms formed of resilient material.

In testimony whereof, I affix my signature 75 in presence of two witnesses.

THOMAS C. SPELLING.
